UNITED STATES PATENT OFFICE.

GEORGE M. BILLS, OF BATTLE CREEK, MICHIGAN.

FASTENER.

1,343,301.

Specification of Letters Patent. Patented June 15, 1920.

Application filed March 6, 1920. Serial No. 363,857.

To all whom it may concern:

Be it known that I, GEORGE M. BILLS, a citizen of the United States, residing at Battle Creek, in the county of Calhoun and State of Michigan, have invented certain new and useful Improvements in Fasteners, of which the following is a specification, reference being had to the accompanying drawings.

10 This invention relates to an improved fastener, and an object of the invention is to provide a very simple, efficient and cheaply made fastener, particularly adapted as a towel hanger and for holding curtains, draperies and various similar articles on display in store windows. It is obvious that handkerchiefs, flags and also decorations may be readily suspended on the wall, wires or cords.

20 Another object of the invention is the provision of a fastener or hanger which may be sold at a reasonable profit, owing to its inexpensive construction, and also the device may be employed for suspending cards and other articles on display.

Still another object is to provide a fastener or hanger comprising two jaws pivotally united, movable flatwise adjacent each other and in corresponding planes, one constituting a main jaw having an offset portion with teeth to be engaged by the fold of the drapery, handkerchief, cards and the like, so that the other or clamping jaw may pass over the article to be suspended to hold the same in place, in combination with yieldable means carried by the main jaw to overlie the auxiliary or clamping jaw to hold the same in position. The auxiliary or clamping jaw has a similar flange to overlie the main or base jaw, thereby additionally holding the two jaws in closed position.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

55 In the drawings:

Figure 1 is a view of the improved

fastener or hanger mounted upon a wire and showing the same holding a curtain, or other drapery,

Fig. 2 is a view in perspective showing the hanger or fastener suspending a towel or the like from a hook,

Fig. 3 is a view showing the two jaws open,

Fig. 4 is a longitudinal sectional view, and

Fig. 5 is a cross sectional view.

Referring to these drawings, 1 designates the main jaw, which is provided with an offset bent portion 2 rectangular in cross section. The material of the jaw beyond the bent portion 2 is bent upon itself as at 3 and the terminal edge of the material beyond the bend 3 is provided with teeth 5 overlying the interior of the offset bent portion 2.

An auxiliary or clamping jaw 6 is pivoted at 7 to the main jaw to move flatwise and in a corresponding plane with the main jaw. One edge of the main jaw has an extension flange 8 bent from the main jaw as at 9, the terminal edge of the flange being folded upon itself to form a bead 10. The auxiliary clamping jaw has one edge provided with a clamping flange 11 bent from the auxiliary jaw as at 12. This clamping flange 11 has its terminal edge folded to form a bead 13. It will be noted that these clamping flanges overlie opposite faces of their respective jaws so that when the jaws flatwise engage the same being moved in corresponding parallel planes will overlie the opposite jaws and hold them in clamping engagement, thereby holding the drapery or other article clamped in engagement with the teeth of the main jaw, a fold of the drapery being adapted to engage the offset angular portion 2 of the main jaw. The two jaws have corresponding registering openings 14 corresponding in shape as shown and in many instances are adapted to engage a headed portion as shown in the drawing so as to suspend a towel or other article in place. It will be noted that the headed member which in the present instance projects from the wall or other stationary support passes through the larger portions of the openings 14 and then the shank of the headed member will engage the narrow parts of the opening, thereby not only suspending the fastener and hanger but also holding the two jaws together so that there is no possible chance of opening the jaws unless the hanger is detached from the headed member.

100

105

110

When suspending a drapery or other article on display from a horizontal wire, cord or the like, the wire or cord is placed between one of the clamping flanges and the body of its jaw, so that when the other jaw is caused to engage the clamping flange, the fastener or hanger will be suspended securely on the wire or cord.

10 The invention having been set forth, what is claimed as new and useful is:—

15 1. A fastener of the kind set forth comprising a main jaw and an auxiliary jaw pivotally united, whereby both jaws may move flatwise and in corresponding parallel planes when closed, the main jaw having an offset part provided with fabric engaging means, between which and the auxiliary jaw a piece of drapery or the like may engage, said jaws having means overlying the opposite jaw to hold the two jaws together.

20 2. A fastener of the kind set forth, comprising a main jaw and an auxiliary jaw pivotally united, whereby both jaws may move flatwise and in corresponding parallel planes when closed, the main jaw having an offset part provided with fabric engaging means, between which and the auxiliary jaw a piece of drapery or the like may engage, said jaws having corresponding registering 25 openings to receive a headed member to hold the two jaws together.

30 3. A fastener of the kind set forth comprising a main jaw and an auxiliary jaw pivotally united, whereby both jaws may move flatwise and in corresponding parallel planes when closed, the main jaw having an 35

offset part provided with fabric engaging means, between which and the auxiliary jaw a piece of drapery or the like may engage, said jaws having means overlying the opposite jaw to hold the two jaws together, 40 said jaws having corresponding registering openings to receive a headed member to hold the two jaws together.

4. In a device as set forth, the combination with a main jaw having a fabric engaging means at one end, an auxiliary jaw pivotally mounted on the main jaw to move flatwise adjacent thereto and in a plane parallel therewith and adapted to overlie the 45 fabric clamping means to hold an article on display in engagement with said means, the two jaws having corresponding registering openings to be engaged by a headed member to hold the jaws together and to suspend the article from a headed member.

5. In a device as set forth, a main jaw having fabric clamping means at one end, an auxiliary jaw pivotally mounted on the main jaw to move flatwise with relation to the main jaw and in a parallel plane therewith so as to overlie the fabric clamping means to hold the drapery in place, the opposite portions of the two jaws having means overlying the respective jaws to clamp them 60 in position, one of said clamping means adapted to engage a supporting wire to suspend the two jaws.

In testimony whereof I hereunto affix my signature.

GEORGE M. BILLS.
